UNITED STATES PATENT OFFICE.

SIMON E. KELLY, OF NEW ORLEANS, LOUISIANA, ASSIGNOR OF ONE-HALF
TO JULES PELLETIER, OF SAME PLACE.

FOLDING KITE.

SPECIFICATION forming part of Letters Patent No. 274,340, dated March 20, 1883.

Application filed July 22, 1881. (No model.)

To all whom it may concern:

Be it known that I, SIMON E. KELLY, a resident of New Orleans, in the parish of Orleans and State of Louisiana, have invented a certain new and useful Improvement in Folding Kites; and I do hereby declare the following to be a full, clear, and correct description of the same, reference being had to the annexed drawings, making a part of this specification.

10 This invention consists, first, in a folding frame composed of a series of ribs pivoted or otherwise connected to a central hub, in combination with a locking-plate for holding the said ribs in expanded or outstretched positions, as will be hereinafter more fully described.

15 It further consists in the combination, with a folding frame composed of the ribs, hub, and locking-plate aforesaid, of a flexible covering adapted to open or close therewith, as is hereinafter described.

20 Figure 1 is a front view of my kite-frame as when opened and ready to receive its covering. Fig. 2 is an enlarged side view of a portion of the frame as when closed. Fig. 3 is a 25 detail showing a plan of the locking-plate, hub, and parts of the ribs. Fig. 4 is a cross-section showing the manner in which the hub and locking-plate are secured together, as well as the means for holding the ribs in extended 30 positions.

25 The letter A designates the hub or central plate, to which the ribs B are pivoted. The periphery of this plate or hub is provided with notches c for the reception of the inner ends of the said ribs, and with a groove, f, for receiving a wire, t, which passes through perforations made in the inner ends of the said ribs, and serves to hold the same in proper positions by tightening the said wire and twisting the 40 ends thereof, as shown at s in Fig. 3.

30 The hub A is provided with a central hole, in which is fitted a pin, p, whereby it is secured within the center of a flanged disk or locking-plate, L, which is likewise provided with a 45 central hole to receive the end of the pin p and permit of the riveting or fastening of the same in such manner that either or both of the aforesaid parts may revolve thereon.

35 The flange of the locking-plate is provided 50 with a series of notches or L-shaped cuts, i,

corresponding in number with the ribs and notches in the hub. The slots i are cut into the flange from the edge thereof, and have their angle portions cut in the same direction, so that the ribs, when dropped into the slots, 55 may be securely held by turning either the hub or locking-plate until the said ribs shall have reached the ends of the angle portions of the cuts.

The outer ends of the ribs are perforated to 60 permit of the passage through the same of a cord or string, x, whereby the said ends are connected and the outer configuration of the kite established.

A perforation, o, is made through the head 65 of the pin p, to provide means for securing the center or lower part of the bridle, the outer or upper ends of which are secured to the ends of the upper ribs in the usual way.

The covering may be of paper or other suitable material. It is secured to the frame, on the flanged side of the locking-plate, by having its outer edges to overlap the string surrounding the same, and by gumming or pasting the folded edges to the main body of the covering. 75

A hole can be made in the center of the covering, through which the head of the pin p can project; or that portion of the pin can be made flat, or nearly so, and the material made to cover the same, as it does the other parts. 80

The hub and locking-plate can be made of any hard material and of any size or configuration, according to the size and style of kite, and, if desired, it can be perforated, as at n, so as to lighten the same. 85

The ribs are preferably made of drawn wire, with each end flattened and perforated, a single hole being made in the end which fits in the hub, and with two holes in their outer ends, so that the surrounding string may be run 90 through one hole, thence half-way around the rib, and through the second hole therein. It is not deemed necessary to show this arrangement in the drawings, as no claim is laid to the same. By turning the locking-plate until the 95 vertical parts of its notches are in line with the ribs will unlock the said ribs and permit of their being folded together for transportation, or to be laid aside until needed.

Having described my invention, what I claim 100

as new, and desire to secure by Letters Patent, is—

1. In a folding kite, the combination, with a series of ribs pivoted or otherwise secured to a central hub, of a locking-plate having notches in the sides thereof for holding the said ribs in expanded positions, substantially as set forth.

2. In a folding kite, the hub A, having a notched and grooved periphery, the ribs B, and wire s, in combination with the locking-plate L, having notched sides, as described, and the

pin p for fastening the hub and locking-plate together, substantially as described.

3. In a folding kite, the locking-plate L, provided with notches i, the hub A, with pivoted ribs B, string x, and the pin p, in combination with the covering, substantially as described, and for the purpose set forth.

S. E. KELLY.
